Primary Examiner — Kelley A Donnelly(74) *Attorney, Agent, or Firm* — Law Offices of Steven W. Weinrieb(57) **CLAIM**

The ornamental design for a portable table, as shown and described.

DESCRIPTION

FIG. 1 is a front, right side, top perspective view of a portable table showing my new design;
 FIG. 2 is a rear, right side, bottom perspective view thereof;
 FIG. 3 is a front elevational view thereof;
 FIG. 4 is a rear elevational view thereof;
 FIG. 5 is a left side elevational view thereof;
 FIG. 6 is a right side elevational view thereof;
 FIG. 7 is a top plan view thereof; and,
 FIG. 8 is a bottom plan view thereof.

The broken lines depict portions of the portable table that form no part of the claimed design.
